AUTOMATIC BRAKING DEVICE FOR PHONOGRAHS AND THE LIKE

Application filed January 31, 1930, Serial No. 424,989, and in Argentina May 10, 1929.

My present invention relates to an automatic braking device for phonographs and the like said device being sensible to the variation of the angular speed of the 5 acoustic arm of the phonograph. These variations take place at the end of the records, when the needle enters a spiral groove or concentric circle.

In order that my invention may be clearly 10 understood and easily carried into practice it has been shown in the appended drawing, wherein:

Fig. 1 is a top view of the apparatus shown in dotted lines.

Fig. 2 is a top view of the apparatus showing a portion of the fly-wheel.

Figs. 3 and 4 show fragmentary perspective views of parts of the apparatus.

Similar reference characters denote same 20 or like parts throughout the said drawing.

Construction.—A vertical projecting rod A is fixed to the acoustic arm of the phonograph, said rod moving on a circular path having its center around the rear end of the 25 arm. This rod will transmit movement to the device proper.

The rod A transmits a rotary movement to the lever C around the pivot D. The lever C has a forked end in which the rod A 30 enters, the other end being provided with a toothed sector E having its center at D.

Said toothed sector E meshes with a toothed wheel G turning on an axle F, said toothed wheel G being fixed to a fly-wheel H.

The axle F is fixed to the end of a second lever I having its center of rotation at N. The opposite end of the lever I is provided 35 with a tooth J.

Said lever is mounted co-axially with the member K which form may be easily seen from the drawing.

The normal resting position of the lever I is determined by the spring L, which pushes it against the stop M fixed on the 45 member K.

In its turn, the position of the member K is determined by the spring O pushing it against the piece P.

The piece P, the form of which may be 50 clearly seen from the drawing, rotates on

the pivot Q and is provided with a braking shoe R and has a V-shaped lever S having its center of rotation at V, said piece S being kept in the position shown in the drawing by means of the spring T and the stop U.

The piece P is brought towards W by means of the spring X, but cannot move, as the end of the lever S rests against the tooth J on the lever I.

Y is the lever on which the brake shoe R 60 is mounted. Z is the periphery representing the rim of the turning-table on which the record is carried.

Operation.—The displacement of the needle and in consequence, of the acoustic 65 arm, while playing a record is from 1 to 2, Fig. 1, and hence, the toothed sector E forming a part of the lever C and having its center of rotation at D will move in an arc from 3 to 4, Fig. 1, due to the action of the

rod A fixed to the said acoustic arm. When the sector E, on its slow turning movement reaches a position such as shown in Fig. 2, it 70 will mesh with the toothed wheel G, forcing this to slowly rotate, together with the fly-wheel H, around the axle F. These uniform

movements will continue while the needle runs within the record groove. However, when the needle reaches the end of the record and enters the usual large spiral groove 75 or eccentric circumference, this will cause an increase in the slow angular speed of the arm. Said increase or acceleration will produce a sudden increase in the speed of

the sector E and this will tend to accelerate 80 the rotation of the system constituted by the toothed-wheel and fly-wheel. However,

as this latter has a considerable moment of inertia with respect to its pivot of rotation 85 F, it will offer a resistance to the increase of speed, and then, the lever I will be carried by the system of pinion and fly-wheel, and it will turn around the pivot N, against

the small action of the spring L. On rotating the lever I, the tooth J sets free the 90 end of the piece S, which, as already explained, is interconnected with the piece P,

this latter being now free and being drawn 95 by the spring X to turn around the pivot Q,

100

whereby the shoe R will be applied against the edge of the turn-table and brake it.

In the meantime, the piece K, drawn by the spring O, will continue resting on the piece P and will in consequence effect a rotation around N, carrying with it the lever I forming part thereof. This displacement will pass the pinion G to the position G', out of contact with the toothed sector E and in consequence, the lever system C and the acoustic arm will be set free to be moved to an adequate position to play a new record.

The system of the members P and S, allows the turn-table to be braked, when desired, by means of the lever Y. In fact, when moving the lever Y downwardly it forces the spring T to recede, but the displacement of N and of the lever S of which it is the center of rotation, makes its end free of the tooth J, whereby the piece P will be free from the influence of X and the shoe R will brake the turn-table.

It is obvious that in carrying out the invention some mechanical details of the device may be altered. For instance, the forked end of the lever C may be suppressed and an elastic means, such as O', may be used to bring it towards the rod A, in which case, the movement of the lever C should be limited by a suitable stop. When using this construction the piece K and spring O may also be eliminated, but the stop M should always subsist, it being fixed to the general frame. This construction has the further advantage of keeping the sector in contact constantly with the pinion.

These different solutions do not depart from the essential scope of the invention, that is, a purely mechanical device, which, using the inertia of a fly-wheel, is sensible to small sudden variation in the angular speed, of the acoustic arm of the phonograph.

It is also obvious that the above device may be used, not only in connection with the braking of phonograph turn-tables, but also in connection with other machines working under similar conditions.

For the braking of phonographs, having an electric motor, the braking device will act on a switch cutting off the current of the motor.

Having now fully described and ascertained the nature of my present invention and in what manner the same is to be carried into practice, I declare that what I claim is:

1. A braking device particularly for phonographs, comprising a rod mounted on an acoustic arm of the phonograph; a pivoted lever cooperating with said rod; a pivotally-mounted brake lever adapted to brake a turn-table of the phonograph; and means including a fly-wheel cooperating with said

pivoted lever and the brake lever whereby, due to the inertia of the fly-wheel relative to its center of rotation, the brake lever is set against the turn-table when the acoustic arm has attained a small sudden increase in its angular speed.

2. A braking device particularly for phonographs, comprising a rod mounted on an acoustic arm of the phonograph; a pivoted lever cooperating with said rod; a pivotally-mounted brake lever adapted to brake a turn-table of the phonograph; means including a fly-wheel cooperating with said pivoted lever and the brake lever whereby, due to the inertia of the fly-wheel relative to its center of rotation, the brake lever is set against the turn-table when the acoustic arm has attained a small sudden increase in its angular speed; and a hand lever to brake the turn-table irrespective of the operation of the fly-wheel.

3. A braking device particularly for phonographs, comprising a pivoted lever cooperating with an acoustic arm of the phonograph; a brake lever adapted to brake a turn-table of the phonograph; and means including a fly-wheel cooperating with said pivoted lever and the brake lever whereby, due to the inertia of the fly-wheel relative to its center of rotation, the brake lever is set against the turn-table when the acoustic arm has attained a small sudden increase in its angular speed.

4. A braking device particularly for phonographs, comprising a pivoted lever cooperating with an acoustic arm of the phonograph; a brake lever adapted to brake a turn-table of the phonograph; a pivoted lever adapted to cooperate with the brake lever; and means including a fly-wheel mounted on the last-named pivoted lever and cooperating with the brake lever whereby, due to the inertia of the fly-wheel relative to its center of rotation, the brake lever is set against the turn-table when the acoustic arm has attained a small sudden increase in its angular speed.

5. A braking device particularly for phonographs, comprising a pivoted lever cooperating with an acoustic arm of the phonograph; a brake lever adapted to brake a turn-table of the phonograph; means including a fly-wheel cooperating with said pivoted lever and the brake lever whereby, due to the inertia of the fly-wheel relative to its center of rotation, the brake lever is set against the turn-table when the acoustic arm has attained a small sudden increase in its angular speed; and means for disconnecting the fly-wheel from the acoustic arm when in the braking position.

6. A braking device particularly for phonographs, comprising a pivoted lever cooperating with an acoustic arm of the phonograph; a brake lever adapted to brake a

turn-table of the phonograph; a pivoted lever adapted to cooperate with the brake lever; means including a fly-wheel mounted on the last-named pivoted lever and cooperating with the brake lever whereby, due to the inertia of the fly-wheel relative to its center of rotation, the brake lever is set against the turn-table when the acoustic arm has attained a small sudden increase in its angular speed; and means for disconnecting the fly-wheel from the acoustic arm when in the braking position.

In testimony whereof I affix my signature.
